Primary Examiner — Philip S Hyder(74) *Attorney, Agent, or Firm* — Kirk A. Buhler; Buhler & Associates Patenting(57) **CLAIM**

The ornamental design for a wedge leveling system, as shown and described.

DESCRIPTION

FIG. 1 is a top perspective view of a tile leveling device, showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a left side elevation view thereof;

FIG. 7 is a right-side elevation view thereof; and,

FIG. 8 is a bottom perspective view.

The broken lines depict portions of the tile leveling device in which the design is embodied that form no part of the claimed design.

1 Claim, 5 Drawing Sheets(56)
